LIQUID OXYGEN APPARATUS

Ewart G. Hickling, Buffalo, N. Y., assignor to The
Linde Air Products Company, a corporation of
Ohio

Application April 20, 1931. Serial No. 531,588

6 Claims. (Cl. 128—140)

This invention relates to a liquid oxygen apparatus, and especially to one adapted for use in airplanes as a means for supplying oxygen gas for breathing purposes while flying at high altitudes.

It is well known that at altitudes of approximately 15,000 feet and higher, the atmosphere becomes too rarefied to sustain consciousness, and an additional supply of oxygen must be provided for aviators reaching such heights. The necessary oxygen supply is usually provided by carrying it in gaseous form under high pressure in heavy cylinders, the weight of each cylinder being some six times that of the oxygen which it contains. This cylinder weight added to the plane load becomes a serious handicap, especially when it is necessary to carry the large quantities of oxygen required for attaining extremely high altitudes or for other long sustained flight. At best a four hour supply is about all that it is possible to carry in this manner. Furthermore, the gas under pressure contains as a rule a certain amount of moisture. Due to the temperature of the atmosphere, and the coldness produced by expansion of the gas, this moisture often freezes in the regulator and causes a partial or complete cut-off of the oxygen supply.

In accordance with my invention I propose to use liquid oxygen as the source of gas supply, whereby the serious disadvantages of carrying the oxygen in the gaseous form are greatly alleviated. I have provided a simple and efficient liquid oxygen apparatus which is light in weight, and will provide a continuous flow of dry oxygen gas to the occupants of the plane whenever desired. Much larger supplies of oxygen may be safely carried with this apparatus, and the gas given off is sufficiently free from moisture to eliminate the hazard of freezing in the delivery pipe or in the regulating mechanism, if used.

The advantages of my invention will be evident from a description of the accompanying drawing showing one embodiment thereof, wherein

Fig. 1 is a plan view of one type of apparatus.
Fig. 2 is an end elevation of the container and support.

Fig. 3 is a section on the line III—III of Fig. 1 showing in detail the bearing construction.
As shown reference numeral 2 represents a liquid oxygen container of the metal vacuum bottle type, and of spherical outer contour. A container capable of withstanding about 5 lbs. gage pressure is suitable. The container is suspended in a gimbal comprising the pivots 3 in a cir-

cular frame 4, the frame being pivoted at 5 to the bracket supports 6 which are rigidly attached to the plane. The supporting axis of the container and that of the frame 4 are at right angles to each other and ball bearings, as shown in Fig. 60 3, are used at all points of support. Thus no matter what position the airplane may assume, the container always remains in an upright position. A filler cap 7 is provided in the top of the container, and the gas outlet pipe 8 also leads 65 out of the top portion. The safety valve 9 acts to prevent excessive pressure within the container. The circular frame 4 is hollow so that gas may flow from the container through the pipe 8, through the bearing 3, a portion of the 70 circular frame and the bearing 5, to the pipe 10 which leads to the point where the oxygen is to be used.

A gas tight connection is provided for the filler cap 7 and this cap is tightened into place immediately after filling the container. Thus all gas evaporated from the liquid oxygen will pass through the outlet pipe 8 and ultimately to the point of use, where a regulator may be provided to control the rate of flow. The normal evaporation of the liquid gas will not in most cases be sufficient for the needs of the pilot, and heating means are therefore provided to stimulate evaporation. This consists of a heating coil 12 within the container, which is connected through the 85 bearings 3 and 5 opposite the gas outlet line and the hollow frame 4 to the pipe 14 leading to the funnel 15. This funnel is mounted on the exhaust pipe 16 leading from the engine of the plane. Air collected in the funnel is warmed by the heat of 90 the exhaust pipe, and the amount of heat delivered to the coil 12 is regulated by the valve 17. Cooling the oxygen delivery pipe 10 about the warm air pipe 14, as shown at 18, will serve to aid in removing the chill from the gas before it passes 95 to the user.

Details of the bearing construction of one of the pivots 3 is shown in Fig. 3, and a similar arrangement is used at all points of support. The hollow cylindrical rod 19 connects at one end with the container 2, and at the other end projects into the casing 21, having a chamber therein. At a necked portion of the chamber are mounted the ball bearings 22 on which the rod 19 revolves. The leather disc 23, attached to the end of the rod 19, acts to prevent passage of oil from the bearings into the chamber, and also prevents any leakage of gas from the chamber. The circular frame 4 connects with the chamber of the casing 21, and, as previously explained, acts as a passage for gas, 110

or warm air, from the pivots 3 to 5. The pivots 5 differ from the one here shown only in the fact that the gas outlet line in one instance, and the warm air line in the other, rather than the circular frame 4, connect with the casing 21. Pivots of this nature will permit a continuous free flow of gas no matter what position the circular frame 4 or the support brackets 6 may assume with respect to the container, which always remains upright.

As much of the apparatus as possible is preferably made of aluminum or an aluminum alloy. This additionally lightens the load on the plane. The size of the container may vary as desired, and the one represented here has a capacity of 10 liters of liquid oxygen. A container of this size, weighing approximately 21 pounds, will easily carry 15 pounds of liquid oxygen, an amount generally considered sufficient for a flight of about four hours at an altitude of around 30,000 feet. The combined weight of the container, the liquid oxygen, and the other parts of the apparatus will add only about 50 pounds to the total load of the plane. To carry an equivalent amount of oxygen in the form of the compressed gas would require ten cylinders weighing about 17 pounds apiece, which, together with the oxygen, would present a total additional load of 185 pounds. Thus a saving in weight of 135 pounds is provided for a total oxygen supply of about 15 pounds. Where larger quantities of gas are desired, the saving in weight is still greater, since the larger size liquid oxygen containers weigh less in proportion to the weight of liquid they contain than do the smaller ones.

Another advantage of this type of apparatus, as previously mentioned, resides in the fact that the gas given off from the liquid oxygen is exceedingly dry as compared with that obtainable from a high pressure cylinder source. There is therefore no danger of the oxygen line freezing up and cutting-off the oxygen supply in a manner which has heretofore happened with the compressed gas, causing very serious results. By providing means for safely and efficiently carrying much larger supplies of oxygen, sufficient for use by the pilot as well as accompanying passengers over long sustained high altitude flight, the invention makes commercially possible a type of flying which heretofore has been more or less experimental in nature.

It will be evident that various modifications in the particular apparatus shown may be made without departing from the spirit of my invention as defined in the appended claims.

I claim:

1. A liquid oxygen apparatus comprising a liquid oxygen container, a support in the form of a frame disposed about said container adapted to freely suspend the container in a constant upright position, heating means within the container for promoting evaporation of the liquid oxygen, means associated with said support for supplying heating energy to said heating means, and means including a portion of said support for conducting oxygen gas from the container to a point of use.

2. A liquid oxygen apparatus for airplanes comprising a liquid oxygen container, a support in the form of a frame disposed about said container adapted to freely suspend the container in a constant upright position irrespective of the position of the airplane, a heating coil within the container, means including a portion of said support for conducting a heating medium to said heating coil to promote evaporation of the liquid oxygen, and means including another portion of said support for conducting oxygen gas from the container to its point of use.

stant upright position irrespective of the position of the airplane, a heating coil within the container, means including a portion of said support for conducting a heating medium to said heating coil to promote evaporation of the liquid oxygen, and means including another portion of said support for conducting oxygen gas from the container to its point of use.

3. A liquid oxygen apparatus for airplanes comprising a spherical liquid oxygen container; a support for said container adapted to freely suspend the container in a constant upright position irrespective of the position of the airplane, said support including a hollow circular frame in which the container is pivoted; a heating coil within the container; means including a portion of said circular frame for conducting a heating medium to said heating coil to promote evaporation of the liquid oxygen; and means including another portion of said circular frame for conducting oxygen gas from the container to its point of use.

4. A liquid oxygen apparatus for airplanes of the type provided with a motor capable of supplying heat comprising a spherical liquid oxygen container; a support for said container adapted to freely suspend the container in a constant upright position irrespective of the position of the airplane, said support including a hollow circular frame in which the container is pivoted; a heating coil within the container; means including a portion of said circular frame for conducting heat supplied by the motor to said heating coil to promote evaporation of the liquid oxygen; and means including another portion of said circular frame for conducting oxygen gas from the container to its point of use.

5. A liquid oxygen apparatus for airplanes of the type using an internal combustion engine comprising a spherical liquid oxygen container; a support for said container adapted to freely suspend the container in a constant upright position irrespective of the position of the airplane, said support including a horizontally pivoted hollow circular frame in which the container is suspended on pivots at right angles to those carrying the frame; a heating coil within the container; means about the engine exhaust pipe for collecting warm air; means including a portion of said circular frame for conducting air warmed by the exhaust pipe to said heating coil when desired to promote evaporation of the liquid oxygen; and means including another portion of said circular frame for conducting oxygen gas from the container to its point of use.

6. A liquid oxygen apparatus for airplanes of the type using an internal combustion engine having an exhaust pipe, comprising a liquid oxygen container, a support in the form of a frame disposed about said container adapted to suspend the same freely in a constant upright position irrespective of the position of the airplane, a heating coil within said container for promoting evaporation of liquid oxygen, means about the engine exhaust pipe for collecting warm air, conduit means associated with said support for conducting air from said collecting means to said heating means, and other conduit means associated with said support for conducting oxygen gas from said container to the point of use.
